(No Model.)

H. W. & J. SITWELL.
SURGICAL WATER BANDAGE.

No. 367,855.

Patented Aug. 9, 1887.

UNITED STATES PATENT OFFICE.

HERBERT W. SITWELL AND JULIET SITWELL, OF RICHMOND, VIRGINIA,
ASSIGNORS OF ONE-THIRD TO CECIL F. SITWELL, OF SAME PLACE.

SURGICAL WATER-BANDAGE.

SPECIFICATION forming part of Letters Patent No. 367,855, dated August 9, 1887.

Application filed October 23, 1886. Serial No. 217,059. (No model.)

To all whom it may concern:

Be it known that we, HERBERT W. SITWELL, a subject of the Queen of Great Britain, and JULIET SITWELL, a citizen of the United States, 5 both residing at Richmond, in the county of Henrico and State of Virginia, have invented certain new and useful Improvements in Physicians' Pads or Bandages; and we do hereby declare the following to be a full, clear, and 10 exact description of the invention, such as will enable others skilled in the art to which it appertains to make and use the same.

This invention relates to devices designed to be applied to the body to modify the temperature thereof.

Devices of this character as heretofore constructed fail to give the best results, for the reason that the fluid used to regulate the temperature passes back and forth through the 20 pad or bandage over the surface under treatment a number of times, thus modifying the temperature of the fluid used, so that at the discharge end of the pad or bandage the temperature of the fluid will approach more nearly 25 to that of the body than at the receiving end of the pad.

The object of our invention is to overcome the objections heretofore found to exist; and to this end the invention consists in a surgical 30 pad or bandage embodying a supply-tube, a discharge-tube, and a number of independent connecting-tubes leading from the supply-tube to the discharge-tube.

It consists, also, in novel features of construction and combinations, which will be fully 35 described in the ensuing specification, and claimed in the claims at the close thereof.

In the accompanying drawing, the figure is 40 a plan view of our improved pad or bandage, a modification being shown in dotted lines.

The pad or bandage shown may be constructed of any light impervious material, though light rubber tubing is recommended.

The pad or bandage consists, essentially, of a 45 feed or inlet tube, A, a discharge-tube, B, and a number of independent circulating tubes, C C, leading directly from the inlet-tube A to the discharge-tube B. The inlet-tube A may be of any convenient length, and is fitted at 50 its receiving end with a perforated plug, a,

by means of which it may be connected with any suitable vessel, D, containing hot or cold liquid, or with a vessel which supplies hot or cold air or vapors. This vessel D may consist of an ordinary wooden bucket containing 55 water and fitted near the bottom with an aperture, d, in which the plug a may be tightly driven. The tube A is closed at its other extremity, a', and is provided with a longitudinal series of apertures to receive the ends of the 60 circulating-tubes C. The discharge-tube is likewise closed at its end b and provided with a corresponding longitudinal series of apertures to receive the opposite ends of the circulating-tubes C. The open or discharge end b' 65 of the discharge-tube B is of such a length that the fluid used may be conducted to any suitable receptacle.

The drawing illustrates a pad or bandage substantially rectangular, with the feed-tube 7c A and discharge-tube B parallel, and the circulating-tubes C C arranged parallel with each other, but at right angles to the feed and discharge tubes; but it will be understood that the specific form may be varied without departing from the spirit of the invention involved, to suit different requirements—as, for instance, in constructing such an appliance for application to the head, it should conform to the contour of the head, and the feed and discharge tubes A and B could not well be maintained in parallelism; but the end sought could be attained, as the circulating-tubes would receive fluid of a given temperature simultaneously from a common supply, (tube A,) and 85 the temperature of the fluid would be but slightly modified in traversing once the length of the circulating-tubes to the discharge tubes.

To maintain the parallelism of the circulating-tubes C C, they may be bound together in 90 any suitable or approved manner, though we prefer to cement their under surface to a film, E, of gutta-percha tissue, as this material is extremely light, (twelve square yards weighing but a pound,) and so flexible that the entire appliance may be rolled into a small compass and carried in the pocket. If preferred, this film or sheet E may be perforated to afford ventilation.

It will be understood, of course, that the 100

supply and discharge tubes are of greater diameter than the circulating-tubes, as they must each carry a greater quantity of liquid or vapor than any one of said circulating-tubes. We have found that a diameter of about one-quarter inch for the tubes A and B and one-eighth for the tubes C C gives good results, but do not confine ourselves to these proportions.

10 The pad thus constructed is extremely light, easily manipulated, and owing to its extreme flexibility readily adapts itself to the portion of the body to which it is applied.

15 We prefer to construct the entire device of light flexible rubber tubing, though in some instances we contemplate using hard rubber for the tubes A and B.

20 The feed or inlet tube A may be arranged, as shown in dotted lines in the drawings, to admit the water or other agent from the source of supply at a point intermediate between the outer circulating-tubes; but we have obtained the best results from the arrangement represented in full lines.

We claim—

25 1. In a pad or bandage for the application of heat or cold to the body, the combination of the inlet or supply tube, the discharge-tube, and a number of independent circulating-tubes connecting the feed-tube directly with the discharge-tube.

2. The combination, substantially as before set forth, of the feed and discharge tubes provided with a longitudinal series of perforations, and the independent circulating-tubes 35 each leading from one of the perforations of the feed-tube to the opposite perforation of the discharge-tube.

In testimony whereof we affix our signatures in presence of two witnesses.

HERBERT W. SITWELL
JULIET SITWELL.
